(57) **CLAIM**

The ornamental design for a display panel or portion thereof with animated graphical user interface as shown and described.

DESCRIPTION

FIG. 1 is a front view of a first image of a display panel or portion thereof with animated graphical user interface showing our new design;

FIG. 2 is a front view of a second image thereof; and,
FIG. 3 is a front view of a third image thereof.

The appearance of the image transitions sequentially between the images shown in FIGS. 1 to 3. The process or period in which one image transitions to another image forms no part of the claimed design.

The dot-dash broken lines define the bounds of the claimed design and form no part thereof. The evenly-spaced broken lines in FIGS. 1-3 depict the display panel or portion thereof and form no part of the claimed design.

1 Claim, 3 Drawing Sheets
